UNITED STATES PATENT OFFICE.

MARTIN BAUER, OF CLEVELAND, OHIO, ASSIGNOR OF ONE-HALF TO
FRIEDERICH J. LANGER, OF CLEVELAND, OHIO.

COMBINED LADDER AND SCAFFOLD.

SPECIFICATION forming part of Letters Patent No. 788,992, dated May 2, 1905.

Application filed October 19, 1903. Serial No. 177,579.

To all whom it may concern:

Be it known that I, MARTIN BAUER, a citizen of the United States, residing at Cleveland, in the county of Cuyahoga and State of Ohio, have invented certain new and useful Improvements in a Combined Ladder and Scaffold; and I do declare that the following is a full, clear, and exact description of the invention, which will enable others skilled in the art to which it appertains to make and use the same.

My invention relates to improvements on a combined ladder and scaffold for which I obtained Letters Patent of the United States December 16, 1902, No. 715,944; and the said improvements consist in certain features and details of construction, substantially as shown, and particularly pointed out in the claims.

In the accompanying drawings, Figure 1 is a perspective elevation of a portion of a building and my improved ladder and scaffold in working relation thereto. Fig. 2 is a plan view or top view of the ladder, enlarged, as compared with Fig. 1. Fig. 3 is an enlarged side view in elevation of a portion of the ladder, with a portion of the scaffold sectioned away to disclose the manner of locking the same in horizontal position. Fig. 4 is a cross-section of one side of the ladder looking down on a line corresponding to $y-y$, Fig. 3; and Fig. 5 is a plan view of the scaffold and a cross-section of the ladder on line $x-x$, Fig. 3. Fig. 6 is a front elevation of a portion of a ladder, showing the scaffold and the bracing-frame and the means for engaging said parts with the ladder and connecting the same, as hereinafter fully described. Fig. 7 is a perspective view from the rear and side of a portion of the ladder, showing one of the locking-dogs for the scaffold or platform; and Fig. 8 is a perspective view of a modification of the dog and a portion of a ladder in which it is engaged.

As thus shown, A represents what may be regarded as an ordinary ladder, having rounds a , as usual, by which to ascend and descend and serving the usual purposes in all respects; but in addition to this I have equipped the ladder with means which provide a scaffold or

platform on which a workman may stand and which is adapted to slide up and down lengthwise of the ladder, according to where the work is to be done, and a bracing and extensible portion B at the top of the ladder which is adapted to slide up and down also in the channels 2 in the side of the ladder in which the scaffold C slides and serves as a brace or rest for the ladder against the building. Said brace or rest is of such length or depth as will support the ladder apart from the building sufficiently to make room for the scaffold C. The idea of a brace or rest for the ladder is not broadly new in this case, the invention being embodied in a form in my Letters Patent above mentioned; but in the said patent the brace or rest B has no range either above or below the comparatively short limitations within which it is adjusted, and hence was not adapted to low buildings and could not be carried up beyond the length of the ladder. I have found that both these limitations are objectionable, and hence have made this improvement, which provides the ladder with an extension E at its top adapted to slide in the grooves or channels 2, as already described, and which itself is equipped with laterally-extending brace or rest B. This extension E may have more or less length relatively, so as to be moved a considerable distance above the end of the ladder itself and also down to approximately near the middle of the ladder or lower, the range of adjustment depending somewhat on the length of the ladder as well as upon the length of the extension. In any event by this construction I obtain a very large accommodation of the ladder to the work and render it useful in places where under the old construction it could not be used at all. The said brace or frame B and platform C are adapted to be folded, and to this end the frame B is provided on each side with a side brace 3, a yoke 4, and a chain 5, from which the yoke is suspended, the said yoke being adapted to embrace the edge of the extension E and to be freely withdrawn therefrom. When the said frame B is folded, the yoke 4 is withdrawn from extension E. The scaffold or platform C

12
likewise is foldable and is provided with side
5 braces 6, pivotally engaged with the frame of
the scaffold at its upper end and with brackets
10 7 on the sliding frame D, which carry the
scaffold. At its rear the scaffold engages
down over a projection 8 and is locked by
15 spring-pressed pawl 9. It follows when the
scaffold is used the parts are supported and
locked in position relatively, as seen in Fig.
20 10; but when folding is desired the pawl 9 is
15 withdrawn and the scaffold is tilted off the
lug or projection 8 and is free to drop down
against the ladder in a folded position.

Both frames D and E are supported in the
15 same channels in the sides of main frame A,
as already described, and both have corre-
sponding mechanism for engaging them with
the ladder as they are adjusted to higher or
20 lower elevations, so that the same reference
characters belong to both. Two forms of
mechanism for locking the said parts upon
the ladder are shown in Figs. 7 and 8, and
either may be used. In Fig. 7 I show a spring-
25 pressed pivoted dog G, behind which there is
a coiled spring d, and when the scaffold D or
extension E is raised or lowered the said part
is first raised to press the dog back, and then
30 the locking-bolts 10 will shoot into the central
orifice 11 and hold the said dog back out
of engaging relation with the recesses or
notches 12 in one edge of grooves or channels
35 2. Frame D or E can then be moved up or
down at pleasure without encountering the
dog to lock the same; but when said locking-
bolts are withdrawn dogs G will be pressed
outward into engaging position by their
40 springs and engage in the first set of notches
12 that come in their pathway. The bolts
10 are withdrawn by pressing the foot upon
45 the pedal 13, and a T-shaped member 14 serves
to operate said bolts through said pedal. In
Fig. 8 the modified form of spring-pressed
dog H is arranged at right angles to that
shown in Fig. 7, and in this case instead of a
50 bolt to lock the dog out of engaging position
the dog is controlled by means of a link 15,
engaged therewith to withdraw the bolt.

A pulley-and-rope mechanism L connects
55 frames D and E, the frame D and platform C
being suspended from frame or extension E
as instead of being engaged with the ladder A, as
formerly. This way both frames and the rope
and tackle can be bodily removed from the lad-
50 der, and this also enables me to avail myself
of the higher elevations to which the scaffold
may be raised by reason of its connection with
the extension-frame E rather than the top of
the ladder.

The brace-frame B is pivoted at 18, and its
60 rear side extension behind said pivot engages
beneath a shouldered extension b, which will
prevent said frame from dropping even if its
support through brace 3 were withdrawn. By
my old construction the ladder was always

6 top-heavy, because the brace frame was con-
fined to the top and could not be lowered
therefrom. By my present construction I
7 can raise the ladder like any ordinary ladder
and then run the brace B and extension E up
as far and as fast as the work may need. A
7 workman can also stand on the platform and
raise the extension E and then pull himself
and platform up and then move said extension
again, and so on till he reaches the top of the
ladder. He can also run both down and re-
move them before the ladder is lowered.

What I claim is—

1. The body of the ladder provided with
guideways extending to the top thereof, an ex-
tension for said ladder and a platform support-
ed from said guideways, means to raise and
lower said platform in respect to said extension,
and means to lock said platform and extension
separately at different elevations, the said ex-
tension and platform having immediate en-
gagement with the body of the ladder, sub-
stantially as described.

2. The ladder having guideways on its sides
running to the top thereof, an extension ad-
justably supported in said guideways toward
its top and a laterally-extending brace for the
ladder on said extension, in combination with
a platform slidably engaging directly in said
guideways and connections from said platform
to said extension constructed to raise and lower
the said platform and to suspend the same
from the said extension, substantially as de-
scribed.

3. The ladder and the extension supported
thereon, a platform slidably supported on the
ladder below said extension, flexible lift mech-
anism for the platform connected with said
extension and separate locking mechanism for
said extension and platform, and means adapt-
ed to be engaged by the foot to operate said
locking mechanism and comprising oppo-
sitely-projecting bolts, substantially as de-
scribed.

4. The ladder and the extension slidably
supported on the top thereof, a platform-frame
slidably supported on the ladder beneath said
extension, and a rope and tackle connecting
said extension and platform-frame, substan-
tially as described.

5. The ladder having grooves inside run-
ning to its top, in combination with a platform-
frame, and an extension-section engaged in
said grooves one above the other, a lock for
each of said parts, and means supporting said
platform-frame from said extension-section,
substantially as described.

In testimony whereof I sign this specifica-
tion in the presence of two witnesses.

MARTIN BAUER.
